CLAIM

The ornamental design for a combined charger and clip, as shown and described.

DESCRIPTION

FIG. 1 is a front perspective view of a charger of a combined charger and clip showing our new design, shown separately for ease of illustration;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the clip of the combined charger and clip shown separately for ease of illustration;

FIG. 10 is a rear perspective view thereof;

FIG. 11 is a front view thereof; FIG. 12 is a rear view thereof; FIG. 13 is a left side view thereof;

FIG. 14 is a right side view thereof;

FIG. 15 is a top view thereof;

FIG. 16 is a bottom view thereof; and,

FIG. 17 is a front perspective view of the combined charger and clip shown in a combined state.

The broken lines in the drawings illustrate the portions of the combined charger and clip, which form no part of the claimed design.
